FEELER MECHANISM FOR LOOMS.

1,392,803.

Specification of Letters Patent.

Patented Oct. 4, 1921.

Application filed October 7, 1919. Serial No. 323,978.

To all whom it may concern:

Be it known that I, ISAAC SNOW, a citizen of the United States, and a resident of Lawrence, in the county of Essex and State of 5 Massachusetts, have invented an Improvement in Feeler Mechanism for Looms, of which the following description, in connection with the accompanying drawings, is a specification, like characters on the drawings 10 representing like parts.

This invention relates to feeler mechanisms for looms, whereby, when the filling in the running shuttle reaches a degree of substantial exhaustion, a train of mechanism 15 is set in operation for effecting replenishment of filling.

The object of the present invention is to provide a feeler mechanism which shall be simple in construction and effective and 20 sensitive in operation.

An important feature of the invention consists of a feeler which is mounted for movement toward and from the front of the loom and is provided with a feeler tip 25 that has a rotary movement in a plane extending longitudinally of the shuttle and is held from such rotary movement by the filling when a working supply is present on a detecting beat and is freed to such rotary 30 movement when, on a detecting beat, the filling is substantially exhausted. In the practical development of this feature of the invention, the feeler is mounted upon a carrier or stand and a feeler tip controller 35 is associated therewith and has operative connection with the rotary feeler tip, the construction being such that when, on a detecting beat, a working supply of filling is present in the shuttle, the feeler and the 40 controller move as a unit under the forward pressure of the surface within the shuttle, but when the filling is substantially exhausted the tip controller and feeler have relative movement as the feeler tip rotates 45 to thereby cause a train of mechanism to effect replenishment of filling.

Other features of the invention and novel combinations of parts will be hereinafter described in connection with the accompanying 50 drawings which show a good, practical form thereof.

In the drawings:

Figure 1 is a perspective view of the detecting part of the loom showing more par-

ticularly the feeler mechanism and its associated parts;

Fig. 2 is a plan view on an enlarged scale showing the action of the feeler mechanism when a working supply of filling is present on a detecting beat; and

Fig. 3 is a similar view showing the action of the feeler mechanism when the filling is substantially exhausted on a detecting beat.

In the drawings the filling replenishing 65 mechanism and other features of the loom construction which are not directly associated with the feeler mechanism, are omitted, since such portions of the loom construction are old and well-known.

The loom frame 1 has mounted thereon the brackets 2, one at each side of the loom, in which is journaled the transverse or rock shaft 3, of usual construction, and from which rises the arm 4 to which is pivoted 75 at 5 the latch 6, the end 7 of which is adapted at times to be engaged by an operating member 8. The operating member 8 may be the cam follower or a part connected thereto.

The lay is provided with the usual shuttle box 9, the front wall of which is slotted at 10 to register with a slot 11 in the wall of the shuttle 12 when the latter is in the detecting box. The shuttle 12 holds the usual 85 filling carrier or bobbin 13 on which the filling is wound, as usual.

Extending from the shipper stand 14 is an arm 15 provided with a slot 16 and to which is adjustably secured the feeler stand 90 17 by means of the bolt 18. The purpose of the feeler stand is to support the feeler and feeler controller in position to perform their respective functions and may be variously contrived, the form of feeler stand 95 shown constituting one good practical form of the invention. As a convenient means of connecting the feeler stand 17 to the arm 16 a bracket 19 may be interposed between the two and to which the feeler stand 17 100 may be connected by means of screws 20.

In the present instance of the invention the feeler stand 17 is provided with an upstanding flange 21 at its rear portion and an upstanding flange 22 at its front portion, 105 in which are guided, in the present instance of the invention, the feeler 23 and the controller 24. The feeler member 23 passes

through an opening 25 in the rear flange 21 and an opening 26 in the front flange 22. A spring 27 interposed between the front flange 22 and a shoulder 28 formed 5 on the feeler 23 normally serves to hold the feeler member in its rearward or feeling position which is defined by a stop pin 29.

Mounted upon the rear end portion of 10 the feeler 23 are the rotary feeler tips 30 and 31. These rotary feeler tips are mounted upon the feeler for rotary movement in a plane extending longitudinally of the shuttle and may be connected to the feeler 15 in any suitable manner. In the present instance, the rear end portion of the feeler is extended laterally and bifurcated at 32, the two rotary feeler tips 30 and 31 being pivotally mounted at 33 and 34, respectively, in 20 the bifurcation of the rear end portion of the feeler.

Mounted upon the feeler stand for movement toward and from the front of the 25 loom is the controller 24, hereinbefore mentioned, which passes through an opening in the rear flange 21, and has its front portion extending through an opening 35 in the front flange 32, a spring 36 being interposed between the shoulder 37 of the controller. 30 Thus the feeler and the controller are each held normally in their rearward position under the impulse of their respective springs 27 and 36, but are free for frontward movement.

35 Each of the rotary feeler tips 30 and 31 is provided with a series of filling engaging teeth 38 which, on a detecting beat, engage a surface within the shuttle and, if a working supply of filling is present, the teeth 40 40 sink into the filling and are held from rotary movement in a plane longitudinally of the shuttle. Each of the rotary feeler tips 30 and 31 is likewise provided with a series 45 of teeth 39 which engage the teeth 40 formed on the rear end portion of the controller 24 which extends between the rotary feeler tips, the construction being such that when 50 the rotary feeler tips 30 and 31 engage a working supply of filling in the shuttle on a detecting beat, and are thereby held from rotary movement in a plane extending longitudinally of the shuttle, the frontward movement of the lay causes the feeler to be 55 pushed frontwardly and, perforce, also the controller 24, so that the feeler 23 and the controller 24 move frontwardly simultaneously. When, however, the filling has 60 become substantially exhausted and the rotary feeler tips 30 and 31 are free to rotate or 65 are not held from rotative movement in a direction longitudinally of the shuttle by the filling, the frontward pressure upon the rotary feeler tips causes a frontward movement of the feeler 23, while the controller 24, being held in its rear position by its

spring 36, causes rotative movement of the rotary feeler tips in a plane extending longitudinally of the shuttle, and relative frontward movement occurs between the feeler and controller. Advantage is taken 70 of this relative movement of the feeler and controller to effect replenishment of filling.

In the present instance the controller 24 has pivoted thereto at 41 the lever 42, one 75 end of which is connected to the feeler 23 by suitable means, such as a pin 43 secured to the feeler and extending into the bifurcated portion 44 of the lever end. The other arm of the lever 42 is connected at 45 with a transmitter 46 which is itself connected at 47 to a lever 48 pivoted at 49 to a stand 50 rising from the loom frame. A finger 51 extends from the lever 48 beneath the latch 6, the construction being such that when the feeler and controller are relatively 80 moved as hereinbefore pointed out, the lever 48 will be actuated to place the end 7 of the latch 6 in the path of movement of the operating member 8 and thereby effect 85 replenishment of filling in a manner well understood.

The rear flange 21 which extends upwardly from the feeler stand may be provided with guide-ways for the feeler and controller, but in the present instance of 90 the invention the flange 21 is slotted, as indicated at 25, Fig. 1, and pins 52 are extended downwardly to form guiding walls for the feeler and controller. The controller has also a pin 53 which limits its rearward movement. By making the rear flange 95 21 slotted as described, the lever 42 may be mounted for swinging movement in the plane of the controller so that when the controller and feeler are relatively moved on a detecting beat and filling is substantially exhausted, the end of the lever 42 may contact with the side of the controller 24, as indicated in Fig. 3, to thereby limit 100 the movement between the feeler member 110 and controller.

In the present instance of the invention the feeler is shown as having two rotary feeler tips mounted thereon and the controller operatively connected to both of the 115 rotary feeler tips by passing between them. The effect of this is that the fine teeth 38 of the rotary feeler tips tend to move in a direction longitudinally of the shuttle transversely to the coils of filling thereon as the 120 feeler moves frontwardly and due to the controller 24 which is normally held rearwardly by its spring 36. This transverse movement of the teeth 38 relative to the coils of filling, enables the rotary feeler tips 125 to be held from rotary movement in a direction longitudinally of the shuttle when a working supply is present, and to cause frontward movement of the controller 24 by their operative engagement therewith 130

- through the teeth 39 and 40. When, however, the filling is substantially exhausted and the coils of filling no longer are able to hold the rotary feeler tips from rotary movement as described, they will be rotated as they move frontwardly by the controller 24 and its toothed engagement therewith, thus causing the feeler and controller to have relative movement. While the invention in its preferred form contemplates the use of two rotary feeler tips mounted for rotary movement in a plane longitudinally of the shuttle, the number of feeler tips may be varied.
- 15 Claims:
1. In a feeler mechanism for looms, the combination of a feeler movable toward and from the front of the loom, having two feeler tips each mounted for rotary movement in a plane extending longitudinally of the shuttle and held from such movement by the filling on a detecting beat until substantial exhaustion thereof, a feeler tip controller having a portion extending between the two feeler tips and mounted for movement toward and from the front of the loom, connections between the rotary feeler tips and controller for effecting simultaneous frontward movement of the feeler and controller when a working supply of filling is present on a detecting beat and permitting relative movement of the feeler and controller when filling is substantially exhausted, and means operated by relative movement of the feeler and controller for effecting replenishment of filling.
  2. In a feeler mechanism for looms, the combination of a feeler and a feeler tip controller mounted for movement toward and from the front of the loom, two rotary feeler tips mounted on the feeler, one at each side of the controller, toothed connections between the feeler tips and controller to cause simultaneous movement of the feeler and controller toward the front of the loom when a working supply of filling is present in the shuttle and the rotary feeler tips are held from rotary movement by the filling and permit relative movement of the feeler and controller when the feeler tips are no longer held from rotary movement by the substantially exhausted filling, and means for effecting replenishment of filling when the feeler and controller are relatively moved.
  3. In a feeler mechanism for looms, the combination of a feeler having a feeler tip provided with a series of gear teeth and mounted for rotary movement in a plane extending longitudinally of the shuttle and held from such rotary movement by the filling on a detecting beat until substantial exhaustion thereof, a controller having a series of rack teeth which engage the gear teeth of the rotary feeler tip to cause simultaneous frontward movement of the feeler and controller by frontward pressure against the feeler tip when a working supply of filling is present and permit relative travel of the gear teeth of the feeler and rack teeth of the controller when the filling is substantially exhausted on a detecting beat, and means for effecting replenishment of filling when the feeler and controller are relatively moved.
  4. In a feeler mechanism for looms, the combination of a feeler having a feeler tip provided with gear teeth and mounted for rotary movement in a plane extending longitudinally of the shuttle and held from such rotary movement by the filling on a detecting beat until substantial exhaustion thereof, a controller mounted independently of the feeler and having rack teeth operatively engaging the teeth of the rotary feeler tip to cause simultaneous frontward movement of the feeler and controller when a working supply of filling is present and permit relative movement of the feeler and controller when the filling is substantially exhausted on a detecting beat, means for yieldingly holding the feeler and controller in rearward position, and means for effecting replenishment of filling when the feeler and controller are relatively moved.
  5. In a feeler mechanism for looms, a feeler provided with a disk-like feeler tip mounted for rotary movement in a plane extending longitudinally of the shuttle and having a series of teeth, a controller movable relatively to the feeler and having teeth co-operating with the teeth of the feeler tip, yielding means tending to move the controller to rotate the feeler tip upon a detecting beat and prevented from effecting such movement by engagement of the feeler tip with the filling until substantial exhaustion thereof, and means operatively connected to the feeler and controller to be actuated by relative movement of the feeler and controller to effect replenishment of filling.
  6. In a feeler mechanism for looms, the combination of a feeler having a feeler tip provided with a series of gear teeth mounted for rotary movement in a plane extending longitudinally of the shuttle and held from such rotary movement by the filling on a detecting beat until substantial exhaustion thereof, a feeler controller mounted independently of the feeler and having a series of rack teeth operatively engaged with the gear teeth on the rotary tip, and means for effecting replenishment of filling when the engaged teeth of the rotary tip and controller cause rotary movement of the tip on a detecting beat.
  7. In a feeler mechanism for looms, a feeler provided with a pair of feeler tips mounted for rotary movement in a plane extending longitudinally of the shuttle, a controller movable relative to the feeler and

operatively connected to both of the feeler tips to rotate them in opposite directions, yielding means tending to move the controller to rotate the feeler tips due to frontward pressure upon the tips and prevented from effecting such movement by engagement of the feeler tips with the filling until substantial exhaustion thereof, and means actuated upon rotation of the feeler tips to effect replenishment of filling.

8. In a feeler mechanism for looms, a feeler provided with a pair of feeler tips mounted for rotary movement in a plane extending longitudinally of the shuttle, a controller tending to rotate both of the feeler tips on each detecting beat due to frontward pressure upon the tips and prevented from effecting such rotary movement by engagement of the rotary tips with the filling until substantial exhaustion thereof, and means actuated upon rotation of the feeler tips by the controller due to frontward pressure upon the tips to effect replenishment of filling.

25 9. In a feeler mechanism for looms, a feeler provided with a pair of feeler tips mounted for rotary movement in a plane ex-

tending longitudinally of the shuttle and having a series of teeth, a toothed rack positioned between the feeler tips and coöperating with the teeth thereof, means for exerting a force upon said rack tending to rotate the feeler tips and prevented from effecting said rotation by engagement of the feeler tips with the filling until substantial exhaustion thereof, and means actuated upon the rotation of the feeler tips to effect replenishment of filling.

10. In a feeler mechanism for looms, a feeler provided with a pair of feeler tips rotatably mounted to engage the filling upon a detecting beat, a controller movable relative to the feeler and operatively connected to the feeler tips, means acting upon the controller tending to rotate the feeler tips and prevented from effecting said rotation by engagement of the feeler tips with the filling until substantial exhaustion thereof, and means actuated upon the rotation of the feeler tips to effect replenishment of filling.

In testimony whereof, I have signed my name to this specification.

ISAAC SNOW.
